Primary Examiner—Sandra L. Morris**Assistant Examiner**—Mitchell I. Siegel**Attorney, Agent, or Firm**—Pearne, Gordon, McCoy & Granger LLP[57] **CLAIM**

The ornamental design for a dishwasher console, as shown and described.

DESCRIPTION

FIG. 1 is a front isometric view of a dishwasher console, showing our new design;

FIG. 2 is a front elevational view thereof;

FIG. 3 is a right side elevational view thereof, the left side being a mirror image thereof; and,

FIG. 4 is a top plan view thereof.

The undisclosed bottom and rear form no part of the claimed design.
